Primary Examiner — Nathaniel D. Buckner*(74) Attorney, Agent, or Firm* — Michael Best & Friedrich LLP(57) **CLAIM**

We claim the ornamental design for a battery pack connector, as shown and described.

DESCRIPTION

FIG. 1 is a perspective view of a battery pack connector showing our new design;

FIG. 2 is a first side view thereof;

FIG. 3 is a second side view thereof;

FIG. 4 is a front view thereof;

FIG. 5 is a rear view thereof;

FIG. 6 is a top view thereof; and,

FIG. 7 is a bottom view thereof.

The regularly spaced broken lines shown in the drawings are included for the purpose of illustrating portions of the article that form no part of the claimed design and the dash dot dash broken lines define the bounds of the claimed design and form no part thereof.
